UNITED STATES PATENT OFFICE.

ADOLPH GOODSTONE, OF NEW YORK, N. Y.

ALARM OR SIGNAL DEVICE OPERATED BY THE FLOW OF GAS TO BURNERS.

Application filed January 22, 1927. Serial No. 162,887.

This invention relates to gas burners of any kind or class, and particularly to the provision of an alarm or signal device in the form of a whistle mounted in the gas line leading to the burner, jet or nozzle whereby the passage of gas through said whistle device will sound an alarm or blast to give warning to an operator or those in a room or compartment; and the object of the invention is to provide in combination with a gas burner, jet or nozzle and the supply of gas thereto, a signal device actuated by the flow of gas therethrough, to give notice of the transmission of gas to the burner and the like, especially when the valve controlling the transmission of gas from the supply to the burner or the like, has been accidentally opened or the flame on the burner or the like extinguished without shutting off the transmission of gas thereto; and with these and other objects in view, the invention consists in a device of the class and for the purpose specified, which is simple in construction and operation, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a plan and sectional view of a burner showing one of my improved devices mounted in connection therewith.

Fig. 2 is a section on the line 2—2 of Fig. 3.

Fig. 3 is a longitudinal section through my improved device indicating its mounting; and,

Fig. 4 is a sectional detail view showing a modified use of the device.

In Fig. 1 of the drawing, I have shown for the purpose of illustrating one use of my invention, a gas burner 5 which may be of any conventional shape, form and construction, the burner 5 having a tube 6 extending radially therefrom, the outer end of which is slightly enlarged to form the mixing chamber 7. On the enlarged end, is an air regulating valve 8 into which the gas discharge tube 9 of a valve 10, coupled with a gas supply line 11 passes.

The above described construction may be of the usual or commonly employed type such as used in single or multiple burner

stoves, ranges and the like. In practice, I mount upon the tube 9, a tubular whistle body 12 which may be of any preferred design and construction, and which in the construction shown, is in the form of an elongated thimble, one side of which is provided with an aperture 13, adjacent its closed end. Mounted within the body 12, is a block 14 having an inclined surface 15, which directs the gas discharge from the tube 9 into the chamber of the body 12 out through the aperture 13, and over the sharp edge 16 on the wall of said aperture, causing the whistle sound. The closed end of the body 12 may also be provided, if desired, with a small discharge aperture 17 through which the gas passing into the closed end of the whistle body may be discharged.

In Fig. 4 of the drawing, I have shown a modification, wherein a whistle body 12^a similar to the body 12 is mounted in conjunction with an illuminating gas burner. In the construction shown, the whistle body 12 is mounted upon the tubular gas supply member 18 which may constitute part of the valve structure, as is common practice. Encircling and in spaced relation to the whistle body 12^a is a tube 19, the upper end of which supports the usual tip 20 for producing the illuminating flame, and the lower end of the tube 19 is provided with apertures 21 controlling the admission of air into the chamber 22 thereof and around the whistle body 12^a in order to mingle the air with the gas discharged from the aperture 13^a in said whistle body, as well as the gas that may be discharged from the small aperture 17^a at the closed end of said body.

In both uses of the invention shown and described, or in any other use thereof, it is desired that the gas leading from the supply pipe directly, or through a valve, passes into and through a whistle body, and the construction and arrangement will be such that when the burner or nozzle of any kind or class is in operation, or in other words, the gas is being burned or consumed in the usual manner, the whistle device will not function to any material degree; but, in the event that the flame be blown out, and the supply continued through the whistle device, a whistle will be sounded to give warning of the faulty operation of the burner or other accessory or device. It will also be apparent, that in the event that the valve controlling the supply of gas to a burner

or the like be accidentally opened, the escape of gas into a room or compartment in its passage through the whistle device, will sound an alarm notifying and informing the occupants of the room or compartment of the inoperative or faulty functioning of the gas burner. In this way, the loss of life or injury to people in a room or compartment, by becoming asphyxiated, is obviated, at least to a material degree, and when the device has been put into use for a short period of time, those utilizing the same will be constantly aware of the conditions of the burner or other gas appliance, and will be enabled to properly control the operation thereof. It will be understood that while I have shown certain details of construction for carrying my invention into effect, that I am not necessarily limited to these details, and various changes in and modifications of

the construction herein shown and described may be made within the scope of the appended claim without departing from the spirit of my invention or sacrificing its advantages.

Having fully described my invention, what I claim as new and desire to secure by Letters Patent, is:—

The combination with a gas appliance having an air and gas mixing chamber and a valve for controlling the transmission of gas into said chamber, of a whistle device coupled with said valve and extending into said mixing chamber and into and through which the gas for supply to said appliance is passed.

In testimony that I claim the foregoing as my invention I have signed my name this 20th day of January, 1927.

ADOLPH GOODSTONE.
